WINDOW STRUCTURE

Charles L. Pettit, Bronxville, N. Y.

Application April 9, 1931, Serial No. 528,757

24 Claims. (Cl. 189—72)

This invention relates particularly to window constructions for tall buildings and the objects of the invention are to provide a practical construction by which the window structure may be more 5 readily harmonized with the architecture of the building; to facilitate the setting up of the windows in the building structure; provide practical and durable weather seals at all joints; to hold the window sash against rattling and to keep the 10 action of the window sash quiet and smooth and easy to operate; to enable ready inspection and repair of the normally concealed sash connections and the like, and to provide a thoroughly desirable construction, which for its advantages will 15 be relatively inexpensive and will be entirely practical commercially.

The foregoing objects are attained by the novel construction, combinations and relations of parts hereinafter disclosed and broadly claimed.

20 The drawings accompanying and forming part of the specification illustrate certain practical embodiments of the invention, but it is to be understood that the structure may be modified as regards the present disclosure without departure 25 from the true spirit and broad scope of the invention.

Fig. 1 is a face view or front elevation of the window structure as incorporated in the building structure; Fig. 2 is an enlarged broken sectional 30 detail as on the plane of line 2—2 of Fig. 1 and showing particularly the weight box and the sash guide plate closing the open inner side of the box; Fig. 3 is an enlarged sectional view as on the plane of line 3—3 of Fig. 1 showing the joinder 35 of two horizontally related window units; Fig. 4 is a broken vertical sectional view as on the plane of line 4—4 of Fig. 1;

Fig. 5 is a broken vertical sectional view as on line 5—5 of Fig. 4;

40 Fig. 6 is a broken detail illustrating the securing of one of the spandrel panels in the sill portion of one window frame;

Fig. 7 is a broken vertical sectional view as on substantially the plane of line 7—7 of Fig. 1;

45 Fig. 8 is a horizontal sectional detail as on the plane of line 8—8 of Fig. 1 illustrating the construction of the spandrel panel;

Fig. 9 is a broken part sectional view of a frame construction for glass panel spandrels;

50 Fig. 10 is a broken sectional detail illustrating another method of securing the spandrels in the hollow sills.

Fig. 1 illustrates an assembly of four window units connected horizontally and vertically to 55 form a continuous vertical panel effect in the

building wall 20. This continuous panel effect may be extended any number of floors to meet the architectural requirements of the building and if desired, the panel effect may be widened to include more than two window units horizontally. Each of the window units consists of a frame made up of a head 21 and sill 22 connected by weight boxes 23.

The weight boxes as shown particularly in Figs. 2 and 3 are of hollow three sided construction secured at top and bottom to the head and sill respectively and arranged with their open sides faced inwardly of the frame and terminating in inwardly directed flanges 24. These hollow shells may be made of relatively light sheet metal 15 reinforced by intermediate partitions 25 dividing the boxes into front and rear compartments for the sash weights 26.

The open inner sides of the weight boxes are closed by the sectional sash guide plates 27 having outstanding, inturned flanges 28, 29, along the front and rear edges and an intermediate T-section parting rail 30, defining guides for the upper and lower sash 31, 32, respectively.

The guide plates are sealed to the weight boxes 25 in the illustration by packing material 33 folded about the inturned flanges 24 of the boxes and held clamped between the reinforcing, sealing and clamping bars 34 at the inside and guide plates at the outside. Screws 35 secure the guide 30 plates and clamp bars and by passing through openings 36 in the weight box flanges 24 definitely locate these parts on the weight boxes.

The guide plates are made up of vertically distinct sections separable on horizontal lines 37, 35 Figs. 4 and 5, which sections can be independently removed upon taking out the screws 35, to give access to interior portions or parts inside the weight boxes. As shown particularly in Fig. 5, the reinforcing, leading or clamp bars 34 cover 40 the joints between adjoining sections of the guide plates and the angle pieces 38, 39, close the joints between the guide plates and the head and sill of the frame. Thus, the structure is tight and weather-proof and at the same time any sections 45 of the guide plates can be readily removed and be as easily replaced.

The upper sections of the guide plates are shown as carrying brackets 40 for the pulleys 41, over which the window weight straps 42 are run so 50 that the removal of the upper guide plate sections enables the taking out of these pulleys for inspection or repair. The pulley brackets are indicated as detachably secured on the back of the guide plate sections by screws 43, with the straps, 55

tapes or chains passing through slots 44 in the guide plates and down and up around pins 45 secured across the flanges of the sash (Fig. 2) and caught beneath the screws 46 set in the heads 5 of the sash. On loosening these screws which are easily accessible in the top of the sash, the tapes may be removed or secured in other adjusted relations, to take up for stretch, or the like.

To prevent the weights from being noisy in the 10 boxes, they may be equipped with bumpers 47 in the form of bands of rubber or other cushioning material seated in grooves 48a surrounding the weights as illustrated in Fig. 5.

To keep the sash quiet, bumpers of rubber or 15 other suitable material may be provided in the upper corners of the upper sash and in the lower corners of the lower sash as indicated at 48, 49, Fig. 5 and bumpers or cushions 50, 51, Fig. 4 in the lower end of the upper sash guide and in the upper end of the lower sash guide to be struck by 20 these sash when they are thrown fully open.

The pulleys are mounted in centered relation over the sash 31 and 32, and this fact, with the provision of adjustable sliding spring shoes 52, 25 secured near the top and bottom in the vertical channels of the sash and sliding in the grooves of the sash guides, together with the special spring weathering strips 53, Fig. 2 held in the pockets behind the inturned flanges 28 and 29 of the 30 sash guide plates and engaging the edges of the sash, insure smooth and quiet operation of the sash.

These weathering strips are shown in Fig. 2 as three sided sheet metal strips 53 seated in the 35 rectangular pockets behind the angular flanges 28, 29, and having bowed spring edge portions 54 bearing against the face of the guide plate and outwardly flared spring wings or flanges 55 bearing against the edges of the sash. This same type 40 of weathering is carried out at the parting rail in a double form of weathering strip 56 caught beneath the T rail and having the outwardly flaring spring wing portions 57 engaging edges of the sash opposite those engaged by the spring flanges 45 55. This construction yieldingly centers the sash in the guides and keeps them weather-tight along the vertical edges. In the channels across the top of the upper sash frame, between bumpers 48 and across the bottom of the lower sash frame 50 between the lower corner bumpers 49, U-shaped weather strips 58 are seated having introverted or 55 reversely bent edges 59, Fig. 4, forming springs to keep this weathering tight. At the meeting rails of the sash, similar weathering may be provided as illustrated in Fig. 4, where the U-shaped strip 58 is shown seated in a groove provided by an outstanding angle piece 60, secured on top of the lower sash frame and adapted to cooperate with an inwardly extending piece 61 secured to 60 the bottom of the upper sash frame.

At the ends, the meeting rails of the sash may be centered and sealed by the wedge blocks 62 secured on the face of the parting rails in position to be engaged by reversely faced wedges 63 65 on the ends of the top extension 60 of the lower sash. The rearwardly projecting extension 61 on the bottom of the upper sash is shown in Fig. 4 as engaging beneath the blocks 62 and thus cooperating with the over-standing portion 60 of the lower sash to close up any gaps at this point.

While each window unit is complete and may be used singly as such, the units are particularly well adapted for being combined in continuous panels after the manner illustrated in Fig. 1. 70

In effecting this result, the horizontally aligned

window frames are combined as shown in Fig. 3 by connecting the weight boxes of horizontally adjoining frames in edge-to-edge relation, as by means of cover plates 64, 65, fastened in the inset portions 66, 67, at the inside and outside portions 5 of the boxes as by means of screws 68 concealed in the weight boxes. These inside fastening screws 68, it will be noted, are readily accessible inside the weight boxes when the sash guide plates are removed. If desired, the frames may be secured in horizontally engaged relation by other means and the inset or shouldered portions 66 and/or 67, be left uncovered to form portions of the architectural details. The covered or "bonded" condition is illustrated in Fig. 1 and this view, 10 with Figs. 4 and 7 shows how the vertical spaces between windows of adjoining floors may be covered by ornamental or other spandrels 69 between vertically aligned window frames and by intermediate spandrels 70 in line with the cover 20 plates 65.

As shown particularly in Figs. 4, 6 and 7, the spandrels 69 may be secured and supported by having their lower edges hooked in engagement over the upstanding flanges 71 on the head of a 25 lower window frame and their upper edges caught behind the dependent flange or lip 72 on the sill of an upper window frame. In the views referred to, the hooked engagement at the bottom is provided by a hook, lug or lugs 73, secured on 30 the back of the spandrel to engage over the upstanding flange 71 on the head of a window frame and the upper edge of the spandrel is locked in position back of the lip of the sill by a wedge or wedges 74, dropped down through an 35 opening or openings 75 in the sill, within the weight box, Figs. 2 and 6, the wedge being indicated in the latter view as shouldered at 76, so that it can be forced over into interlocked engagement beneath the sill and held thus by small 40 wedges 77 dropped into position at the opposite side of the shouldered wedge. In placing the spandrels, as with locating the other parts, suitable calking may be employed as indicated at 78 in the several views to make the proper weather-tight joints between the window parts and building structure.

To prevent the weight of the spandrels from crushing down the hollow heads of the window frames, filler pieces 79 may be inserted in the 50 hollows of these heads as shown in Fig. 4 to transmit the weight of the spandrels 69, 70, to the vertical member of the weight boxes and sash guides.

The intermediate spandrels 70 are indicated in 55 Fig. 7 as held in position by the intermediate cover plates 65, the latter having portions 80 overlapping the edges of the intermediate spandrels.

Fig. 8 illustrates how the spandrels may be bonded to the wall surfaces at the outside edges 60 by suitable calking 78 and this view also shows how the spandrels may be made up as channelled frames 81 having the spandrel panels 69, set in the grooves of the same. This construction may be modified as in Fig. 9, which illustrates 65 a corner of the spandrel frame within the top bar of the frame removably held in place by the lug member 83 secured in the channel of the top bar by screw 84 and hooked over the end and into the outer channel of the side bar of the frame, where 70 it is removably held by screw 85. Such a spandrel frame is well adapted for holding a panel 86 of glass, bright metal, vitreous material, or the like.

Instead of only the hooks at the bottom, the 75

spandrels may have hooks at the top as illustrated in Fig. 10, where hook lugs 87 are shown provided at the forward upper edge of the spandrel engaged over the inwardly hooked lower edges 88 of the lip of the sill, eliminating the need for the wedges 74.

As shown particularly in Figs. 4 and 10, an angle piece 89 may be welded or otherwise secured on the underface of the sill back from the lip 72 of the sill in position to fit the wall in back of the spandrels. This angle thus positions the sills of those frames which carry the spandrels, and as particularly shown in Fig. 4, form abutments for the spandrel holding wedges 74, the same being substantially in line with the wedge openings 75 in the top of the sill.

The spring weather strips 58, Fig. 4, in the channels in the top of the upper sash and in the bottom of the lower sash, when not compressed project slightly beyond the edges of the sash substantially flush with the bumpers in the corners of the sash, so as to make effective sealing engagement with the head and sill portions of the frame.

The pulleys are mounted on the back of the upper sections of the sash guide plates to carry the sash chains or straps up through the slots in the guide plate in exactly centered relation to the sash, so the natural tendency of the sash is to run true. But, in addition, the spring weather strips in the pockets of the sash guide plates engage opposite faces of the sash to prevent rattle and the adjustable spring sliding shoes near the upper and lower corners of the sash guide and hold the sash against edgewise movement. The guide plates are completely sealed to the weight boxes, but may be easily taken off and replaced in sections without injury to such sealing. The cover plates between adjacent window frames are attached by screws disposed inside the weight boxes and hence are entirely concealed in the finished structure. The spandrels are secured at top and bottom, either by hooks at top and bottom or by hooks at the bottom or wedges at the top, back of the lip of the sill and the weight of these spandrels is transferred to the vertical members of the frames, which are well capable of sustaining such weight.

What is claimed is:

1. A window structure, comprising window frames constructed as separate units, means for connecting the same together in horizontal relation and spandrels connecting vertically spaced window frames in vertically continuous panels of windows.

2. A window structure, comprising window frames constructed as separate units, means for connecting the same together in horizontal relation, spandrels connecting vertically spaced window frames in vertically continuous panels of windows, said spandrels comprising main spandrels connecting the heads and sills of vertically spaced window frames and intermediate spandrels between the main spandrels and disposed in line with the spaces between horizontally adjoining window frames.

3. A window structure, comprising window frames constructed as separate units, means for connecting the same together in horizontal relation, spandrels connecting vertically spaced window frames in vertically continuous panels of windows, said spandrels comprising main spandrels connecting the heads and sills of vertically spaced window frames, intermediate spandrels between the main spandrels and disposed in line with the

spaces between horizontally adjoining window frames and cover plates joining the horizontally adjoining window frames in vertical alignment with said intermediate spandrels.

4. A window frame comprising a head, a sill and hollow weight boxes connecting said head and sill and open to the interior of the frame, removable sash guide plates closing the open inner sides of the boxes and means for detachably securing said sash guide plates in position, said sash guide plates consisting of vertically separable sections which can be removed independently of each other.

5. A window structure comprising a frame made up of head and sill, connected by a hollow weight box open to the interior of the frame and a sectional sash guide plate covering the open side of the box and removable in sections to expose different portions in the length of the weight box.

6. A window frame having a hollow weight box open to the interior of the frame and having opposed flanges at said open side of the same, a removable sash guide plate overstanding said flanges, means for detachably securing said sash guide plate in position, including bars engaged behind said flanges and fastenings extending between the bar and plate through the flanges, said sash guide plate consisting of vertically separable sections disposed with their adjoining ends bridged by the bar aforesaid.

7. A window frame provided with sash guides, upper and lower sashes operating in said guides, weathering in the guides for said sashes, bumpers in the upper corners of the upper sash and in the lower corners of the lower sash and bumpers for the upper sash in the lower ends of the upper sash guides and for the lower sash in the upper ends of the upper sash guides.

8. A window frame having weight boxes open to the inside of the frame, sash guide plates covering the open inner sides of the weight boxes and having removable upper sections and sash weight pulleys supported on the backs of said removable guide sections and removable with said sections.

9. A window frame, sash operating in said frame, said sash having resilient bumpers in the upper and lower corners of the same and weathering across the top and bottom of the sash substantially flush with said bumpers and arranged to project slightly beyond the upper and lower edges of the sash.

10. In combination, window frames having hollow weight boxes open at the inside of the frames, plates for securing the weight boxes of adjoining window frames together, fastenings for said plates accessible inside the weight boxes through the open sides of said weight boxes and sash guide plates closing said open sides of the weight boxes and removable to provide access to the interiorly located fastenings for the securing plates.

11. In combination, a window frame having a sill portion and weight box, said sill portion having an opening through the same within the weight box, a spandrel engaged in the sill portion and holding means for the spandrel entered through said opening within the weight box.

12. In combination, a window frame having a sill portion and weight box, said sill portion having an opening through the same within the weight box, a spandrel engaged in the sill portion, holding means for the spandrel entered through said opening within the weight box and a locking device for said holding means.

13. A window structure comprising window frames constructed as separate units and ar- 75

ranged horizontally in rows and with horizontal rows superposed in vertical alignment, cover plates connecting the horizontally related window frames in said horizontal rows and spandrels connecting vertically related rows of the window frames in vertically extending panels of windows.

14. In a window construction, a frame formed of extruded metal and including side jambs, a weight-hung sash slideable in said frame, a cut-out portion forming an opening in said jambs for permitting access to the sash weights, and a strip adapted to cover each jamb and opening, said strips being formed with guide means adapted to interengage with said sash whereby to permit sliding movement of the sash.

15. In a window construction, a frame formed of extruded metal and including side jambs, a weight-hung sash slideable in said frame, a cut-out portion forming an opening in said jambs for permitting access to the sash weights, and a strip adapted to cover each jamb and opening, said strips being formed with ribs adapted to seat in the sides of the sash and form a guide means therefor to permit sliding movement of the sash.

16. In a window frame construction, slideable sashes in said frame, a parting stop mounted on said frame intermediate said sashes, and inter-engaging means on one of said sashes and on said parting stop for providing a weather-tight seal when said sash is in closed position.

17. In a window frame construction, a slideable sash in said frame, a parting stop mounted on said frame, and inter-engaging flanges on said sash and parting stop for providing a weather-tight seal.

18. In a window construction, a frame therefor, stiles provided in the sides of and forming a part of the permanent frame construction, sashes having their side rails provided with spaced ribs slideable in said stiles, said stiles being provided with inwardly extending projections adapted to seat against the sides of said ribs to form a line contact therewith whereby to provide a weather-tight seal therebetween.

19. In a window construction, a frame therefor, pairs of spaced stiles in said frame, each stile being provided with a channel, sashes provided with spaced ribs slideable in said channels, said channels having inwardly projecting resilient flanges adapted to form a line contact with

said ribs and provide a weather tight seal therewith.

20. In a window construction, a frame therefor, sashes slideable in said frame and provided with rails having spaced ribs, stiles in said frame and provided with spaced channels adapted to receive said ribs, said channels being formed with inwardly extending flanges adapted to form a line contact with said ribs and provide a weather-tight seal therewith. 10

21. In a window construction, a frame therefor, individual stile members each formed with a longitudinal channel and a laterally extending portion, removable means seating on said extending portions for detachably retaining said members in position, sashes having spaced ribs slideable in said channels, and inwardly extending flanges on said members and adapted to form a line contact with said ribs whereby to provide a weather-tight seal therewith. 15

22. In a window construction, a frame therefor, sashes slideable in said frame and provided with rails having spaced ribs, and individual, resilient stile members in said frame, each adapted to receive one of said ribs and form a weather-tight seal therewith, and each of said stile members being individually removable whereby they may be readily assembled or replaced. 20

23. In a window construction, a frame therefor, pairs of spaced stiles in said frame, each stile being provided with a channel, sashes having spaced ribs and slideable in said channels, said stiles being provided with inwardly projecting resilient flanges adapted to contact said ribs and form a weather-tight seal therewith, the ends of said flanges forming but a line contact with said ribs whereby said sashes may slide freely in said channels with a minimum of resistance. 35

24. In a window construction, a frame therefor, slideable sashes in said frame and having rails provided with spaced ribs, stiles provided with spaced flanges adapted to receive said ribs but spaced therefrom, and projections on said flanges adapted to engage the sides of said ribs and form a line contact therewith, said flanges and projections being resilient whereby to receive and engage said sides and form a weather-tight seal therewith even though said sides vary in thickness. 45

CHARLES L. PETTIT. 50
